US00D830766S

(12) **United States Design Patent** (10) **Patent No.:** **US D830,766 S**
(45) **Date of Patent:** **** Oct. 16, 2018**

(54) **CREAMER LID**

(71) Applicant: **Helen of Troy Limited**, Belleville, St. Michael (BB)

(72) Inventors: **Lyndon Treacy**, Brooklyn, NY (US); **Paul Mulhauser**, New York, NY (US)

(73) Assignee: **Helen of Troy Limited**, St. Michael (BB)

(**) Term: **15 Years**

(21) Appl. No.: **29/597,464**

(22) Filed: **Mar. 17, 2017**

(51) **LOC (11) Cl.** **07-99**

(52) **U.S. Cl.** **USPC** **D7/392**

(58) **Field of Classification Search**

(57) **CLAIM**

The ornamental design for a creamer lid, as shown and described.

DESCRIPTION

FIG. 1 is a top, front, right side perspective view of a creamer lid, showing my new design;

FIG. 2 is a top, rear, left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a top, front, right side perspective view shown in condition of use.

The broken lines shown in FIG. 8 depict portions of the creamer lid that form no part of the claimed design. The broken lines shown in FIG. 9 depict environmental subject matter that forms no part of the claimed design.

1 Claim, 9 Drawing Sheets
